[57] CLAIM

The ornamental design for a parenteral infusion pump, substantially as shown.

DESCRIPTION

FIG. 1 is a perspective view of a parenteral infusion pump embodying our new design;

FIG. 2 is a top view of the pump shown in FIG. 1;

FIG. 3 is a side view of the pump showing the side opposite that shown in FIG. 1;

FIG. 4 is a rear view of the pump shown in FIG. 1;

FIG. 5 is the bottom view of the pump shown in FIG. 1.

The cables, shown in broken lines in the several views are disclosed for illustrative purposes only and form no part of the claim.

Fig. 1.

Fig. 2.

FIG. 4.

FIG. 3.

FIG. 5.
